CLAIM

The ornamental design for a baby monitor, as shown and described.

DESCRIPTION

FIG. 1 is a perspective view showing a baby monitor according to my novel design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The portions of the baby monitor shown in broken lines are included for the purpose of illustrating unclaimed portions of the baby monitor and form no part of the claimed design.
